UNITED STATES PATENT OFFICE

CHARLES H. TOMLINSON, OF MANSFIELD, OHIO, ASSIGNOR, BY MESNE ASSIGNMENTS, TO THE OHIO BRASS COMPANY, OF MANSFIELD, OHIO, A CORPORATION OF NEW JERSEY

COUPLER

Application filed June 5, 1928. Serial No. 283,006.

My invention relates to couplers and particularly that class of couplers known as the Janney type.

The object of my invention is to provide a coupler in which all relative movement of the connected heads is eliminated and the stress upon the pin and upon the lock is reduced to a minimum.

In the present types of commercial couplers of the Janney type the coupled heads are free to move relative to each other to a very large degree, which means enormous wear of the parts and unusual breakage and in the case of passenger car operation the looseness between the coupler heads permits continual annoying jolts to the passengers and each car is permitted to move more or less independently of the other as the train travels along.

20 In my device the coupled heads are held absolutely immovable relative to each other and the train moves as a unit and without a majority of the jar and vibration which is usually found in cars equipped with the ordinary types of couplers. My invention resides in the new and novel construction, combination and relation of the various parts herein described and shown in the accompanying drawings.

30 In the drawings:

Fig. 1 is a face or end view of my invention.

Fig. 2 is a side view of two coupled heads shown in Fig. 1 without the spring draw bars which connect the coupler heads to the cars.

35 Fig. 3 is a view in section of Fig. 1 taken on the line 3—3 and shows the interior parts of my invention in connection with two coupled heads.

40 Fig. 4 is a top plan view of one of the knuckles which I employ.

Fig. 5 is a section on the line 5—5 of Fig. 4.

45 Fig. 6 is a vertical section on the line 6—6 of Fig. 3 and shows the interlocking of the knuckle with the head to relieve the coupling pin of stress.

50 In the preferred embodiment of my invention I employ a body member 1 which has a recess 2 in which is mounted a horizontally movable spring lock comprising the

locking member 3 which has a wedge shaped face 4 to engage the tail of a knuckle and a flat face 5 to engage the inner side wall of the coupler body and has secured to the end face a guide rod 6 which reciprocates in the stationary guide block 7. Guide strips 8 secured to the upper and lower walls of the coupling head also guide the locking member 3. A spring 9 continually urges the locking member in a forward direction when two coupler heads are interlocked.

Projecting laterally from the body member 1 are abutment members 10 and 11. The abutment member 10 is provided with a passage or opening 12 which has a bell shaped mouth 13 to better guide into the opening 12 a pin 14 having a bevelled end face 15 and projecting from the abutment member 11. The opening 12 may be of any suitable shape in cross section and the pin 14 will have a shape corresponding thereto. Surrounding the bell shaped mouth 13 is a flat surface 16 to engage with the flat face 17 surrounding the pin 14. When two couplers are connected the faces 16 and 17 are in close engagement and the interconnecting of the pins 14 with the openings 12 will absolutely prevent any relative transverse movement of the heads or relative rotative movement about a common longitudinal axis. Hence there will be no continual wear to the pins or openings or faces while the couplers are in operation.

In order to prevent relative longitudinal movement of two coupled heads, I employ knuckles of the Janney type which are pivotally secured to their respective heads by means of the pins 18. Each knuckle comprises a hook-shaped portion 19 having a face 20 which engages with a like face of a knuckle on a cooperating coupler. Each knuckle is provided with an oblong hole 21 through which passes the pin 18. The hole 21 is made oblong to facilitate the coupling and uncoupling of two heads and to relieve the stress upon the pin after the heads are coupled, as later explained.

The tail portion 22 is provided with abutments 23 whereby is formed a transverse groove 24 on the upper and lower face of the tail and having faces 25. Projecting up-

wardly and downwardly from the inner surfaces of the body member 1 are ribs or abutments 26 having faces 27 which are arranged to be engaged by the faces 25 of the abutments 23 when the heads are in coupled relation. The ribs 26 ride in the transverse grooves 24 of the knuckle.

The relation of the ribs 26 with respect to the abutments 23 and the oblong hole 21 with respect to the pin 18 is such that when two heads are coupled, the relation of the oblong hole with respect to the pin 18 will permit the abutments 26 to be engaged by the abutments 23 and permit clearance between the walls forming the hole 21 and the pin 18. This construction removes all or practically all pulling stress upon the pin 18 when two heads are coupled and the stress is taken up almost exclusively between the abutments 23 and 26, both of which can be made large and substantial as compared with the pin 18.

When two heads are brought together in coupled relation with the faces 20 of the knuckles engaging and the knuckles moved in a coupling direction as far as possible, the result will be to draw the faces of the coupler heads into engagement with each other and I do not provide any limit stop as to the movement of the knuckles in a coupling direction so that it is always possible to draw the heads into tight engagement with each other.

The wedge lock 3 engages the tapering face 28 of the knuckle and moves the knuckle in a locking direction as far as necessary to hold the faces of the heads in coupled position and the wedge under the action of the spring 9 is constantly urging the knuckle to move in a locking direction, thereby constantly tending to draw the coupler heads into tighter engagement. This construction permits of taking up inequalities which may be present in any two coupler heads and always permits the tight locking of two heads, which would not be the case if there was a limitation as to the movement of the wedge lock 3 or the knuckle.

At the same time under pulling action or stress the tendency for the knuckle to act as a bell crank pivoting about the pin 18 and thereby bringing pressure upon the wedge 3 tending to push the wedge backward is materially reduced through the engagement of the abutments 23 and 26 and this has a decided advantage when it is desired to uncouple two heads in that the pressure between the knuckle and the wedge lock 3 is found to be so reduced that the friction is accordingly reduced, which permits easily retracting the wedge lock 3.

60 The wedge lock 3 can be manipulated by the lever 29 or by other suitable means.

The knuckle is provided with upwardly and downwardly projecting lugs 30 which may contact with the portion 31 of the coupler head when the couplers are first brought

together under impact, thereby removing stress upon the pin 18, although if proper clearances are allowed the impact will come entirely upon the faces of the couplers.

The surfaces 25 and 27 may be eccentric with respect to the center point or axis of the hole 21 in the knuckle or of the pin 18. In Fig. 4 I have shown the center of the radius R of the surface 25 as positioned at a point distant from the axis of the hole 21, therefore the surface 25 is eccentric to the axis of the hole 21.

In order to move the knuckles to an open position automatically upon withdrawing the wedge lock 3, I use a reciprocating plunger 32 continually pressed toward the knuckle by means of the spring 33.

The longitudinal axes of two coupled heads are held in fixed relation to each other and the longitudinal movement of two heads is limited to merely that which may be allowed by a spring in the materials used and the constant tendency is for the wedge lock 3 to draw the heads into tighter engagement and the pins 14 interlocking with the openings 12 on two coupled heads prevents relative rotative movement about the axes or a relative transverse movement of the heads in any direction. Therefore, it will be seen that two connected coupler heads will form practically the equivalent of a rigid bar connecting two cars and the only longitudinal movement between the coupler and the car body is that in the spring draft gear.

It will be evident that if there is no relative movement of the parts of two coupled heads, wear is eliminated almost entirely. Also, any movement between the knuckle and the wedge lock is eliminated or reduced to a very small amount. Also, the pulling stress is taken up entirely or to a very large degree directly between the knuckle and the coupler body and therefore the direct pull upon the pin 18 is eliminated or materially reduced and there is only a component side stress thereon. Also since the pulling stress is largely between the abutments 23 and 26 the pressure between the tail 22 and lock 3 is relatively small and the lock 3 may therefore be easily retracted.

The construction of my improved coupler head is such that the same may be coupled to any of the present standard couplers of the Janney type such as are known as the M. C. B. and the A. R. A.

My improved coupler is well adapted to have attached thereto, air, steam, water and electric connections which are coupled automatically upon bringing together two cars and are held in a fixed coupled relation while the coupler heads are together.

The curvature of the surfaces 25 and 27 on the abutments 23 and 26 may be so related that as the wedge lock 3 crowds the tail 22 to one side, the surfaces 25 and 27

contacting will force the knuckles rearwardly and simultaneously the forward end of the knuckle will move rearwardly and hence if coupled to a cooperating head, the two will be drawn towards each other and their faces into strong engagement. The said action of the knuckles will take place on each head. The wedging action of the locks 3 draws the contact faces 20 of the hook shaped portions 5 of the knuckles together at all times when coupled, irrespective of the draw bar pull, and this in turn draws the knuckles outwardly, holding the surfaces of the abutments 23 and 10 26 tightly together so that their friction engagement will resist opening of the knuckles 15 even when the train is slack.

There will be modifications to my improved coupler herein disclosed which will be evident to those skilled in the art. Therefore, 20 I wish to be limited only by my claims.

I claim:—

1. A car coupler head having a contact face for limiting movement of said head toward the head of a connected coupler, a loosely pivoted coupler knuckle on said head for holding said face in contact with the corresponding face of a connected coupler head and eccentric abutments on said knuckle and head respectively arranged to shift said 25 knuckle bodily transverse to its pivotal axis for drawing said faces together when said knuckle is swung about its axis to closed position.

2. A car coupler comprising a coupler head 30 having a contact face for engaging a contact face of a connected coupler, a coupling knuckle loosely pivoted on said coupler head for connecting said coupler with another coupler, a lock for holding said knuckle closed 35 and members on said knuckle and said coupler head respectively, having cam engagement with each other for retracting said knuckle and drawing the contact faces of said couplers together, said members having a range 40 of movement beyond that required for bringing 45 the contact faces together.

3. In combination a coupler head having a contact face for engaging a similar face on a connected coupler, a coupler knuckle pivotally mounted on said head and movable longitudinally thereof, and eccentric abutment members for retracting said knuckle, said abutment members having a range of relative movement beyond that required for drawing 50 the contact faces of said couplers together.

4. A coupler head having a coupler knuckle pivotally mounted thereon and movable longitudinally thereof, said coupler head having a contact face for engaging a contact face 55 of the connected coupler and for limiting movement of said couplers toward each other and eccentric abutments for retracting said knuckle when said knuckle is rotated about its pivot to draw said contact faces together, 60 said eccentric abutments having a range of

movement beyond that required for drawing said contact faces into contact with each other.

5. A car coupler comprising a coupler head, a knuckle pivotally mounted on said head and movable longitudinally thereof, abutment members on said knuckle and head respectively and spaced radially from the pivotal axis of said knuckle for receiving the load on said knuckle, said coupler head having a contact face for engaging a contact face on a connected coupler and for limiting the movement of said couplers toward each other, said knuckle having a range of movement beyond that required to bring said contact faces together, and a wedging member for swinging said knuckle about its pivot, said abutment members being held in tight frictional engagement with each other for resisting reverse pivotal movement of said 70 knuckle at all times when coupled independently of draft on said coupler.

6. A coupler head having a contact face to engage the face of a connected coupler and limit movement of said couplers toward each other, a coupling knuckle pivotally mounted on said head and having limited movement longitudinally of said head and eccentric abutment members co-acting between said knuckle and its head for retracting said 90 knuckle when said knuckle is swung to a closed position and for receiving the force of the load on said knuckle, the frictional engagement between said abutment members acting to resist reversed pivotal movement 100 of said knuckle under said load, said knuckle having a range of movement beyond that required to bring said contact faces together and a wedging lock for swinging said knuckle to closed position.

7. A coupler head having a contact face for engaging a contact face of a connected coupler, a knuckle loosely pivoted on said head for holding said contact faces together, said knuckle having a range of movement beyond 105 that required to bring said faces together, a wedging lock for holding said knuckle closed and frictional abutment members spaced from the pivotal axis of said knuckle for resisting opening of said knuckle, said frictional abutment members being drawn together by the force of the load on said couplers but being held in engagement by the wedging lock even when there is no load on the couplers.

8. A car coupler comprising a coupler head, a knuckle pivotally mounted on said head, abutment members on said head and knuckle respectively and spaced radially from the pivotal axis of said knuckle for receiving the load on said knuckle, said coupler head having a contact face for engaging a contact face on a connected coupler and for limiting the movement of said couplers toward each other, a wedging member for swinging said knuckle about its pivot and a spring 115 120 125 130

having telescopic engagement with said wedging member for actuating said wedging member, said abutment members having frictional engagement with each other for resisting reverse pivotal movement of said knuckle when coupled and being held in tight frictional engagement by said wedging members even when there is no load on the coupler.

9. A car coupler comprising a coupler head having a contact face for engaging a contact face of a connected coupler, a coupling knuckle loosely pivoted on said coupler head for connecting said coupler with another coupler, a lock for holding said knuckle closed, a spring having telescopic engagement with said lock for actuating said lock, and members on said knuckle and said coupler head respectively, having cam engagement for retracting said knuckle and drawing the contact faces of said couplers together, said cam and knuckle having ranges of movement beyond that required for bringing the contact faces of said couplers together.

10. A coupler head having a contact face for engaging the contact face of a connected coupler, a knuckle loosely pivoted on said head for holding said contact faces together, said knuckle having a range of movement beyond that required to bring said faces together, a wedging lock for holding said knuckle closed, an actuating spring for said lock having telescopic engagement therewith, and frictional abutment members spaced from the pivotal axis of said knuckles for resisting opening of said knuckle, said frictional abutment members being drawn together by the force of the load on said couplers and being held in engagement by the wedging lock even when there is no load on said coupler.

11. A car coupler head having a contact face for limiting movement of said head toward the head of a connected coupler, a coupling knuckle pivoted on said head for holding said head to the head of said connected coupler, and means comprising cam surfaces on said knuckle and head respectively for retracting said knuckle bodily relative to said contact face to draw said contact face against the face of the connected coupler.

In testimony whereof I affix my signature.
CHARLES H. TOMLINSON.
